UNITED STATES PATENT OFFICE.

ROBERT H. STOCKTON, OF ST. LOUIS, MISSOURI.

DESIGN FOR A RANGE.

SPECIFICATION forming part of Design No. 35,194, dated October 15, 1901.

Application filed April 8, 1901. Serial No. 54,935. Term of patent 14 years.

To all whom it may concern:

Be it known that I, ROBERT H. STOCKTON, a citizen of the United States, residing in the city of St. Louis, in the State of Missouri, have invented and produced a new and original Design for a Range, of which the following is a full, clear, and exact description, reference being had to the accompanying drawings, forming part of this specification.

Figure 1 is a perspective view of my design. Fig. 2 is a side elevation of the same.

As shown in the drawings, the leading or material features of my design consist of the rectangular body 1, surmounted by a vertical

extension 3 at its rear side, and a pipe connection 2, having vertical side walls extending rearwardly from the rear wall of the body 1 and having a rear wall extending at an incline from the rear vertical face of the rectangular body and then vertically to the upper terminus of said connection.

I claim as my invention—

The design for a range herein shown and described.

ROBERT H. STOCKTON.

In presence of—

E. S. KNIGHT,
N. V. ALEXANDER.
